COLLAPSIBLE DISPLAY FORM FOR FOOTWEAR

William N. Norman, Chicago, Ill., assignor to Ripon Knitting Works, Ripon, Wis., a corporation of Wisconsin

Application March 30, 1955, Serial No. 497,894

8 Claims. (Cl. 35—57)

This invention relates to improvements in display forms for footwear and more particularly to a novel collapsible cardboard form suitable for displaying slipper socks and the like.

Although footwear display forms of various types have been widely used heretofore for displaying socks and the like, such display forms have been characterized by a rigid molded construction which is relatively heavy and expensive. Accordingly, there has been a definite need for a lightweight inexpensive footwear display form which is also easy to ship and to use.

A primary object of my invention is to provide a novel and improved display form for footwear which is relatively cheap and of lightweight construction.

A further object of the invention is to provide a novel collapsible footwear display form made of cardboard or the like.

Another object of the invention is to provide an inexpensive collapsible foot form which is especially adapted for displaying slipper socks and the like.

Other objects and advantages of the invention will become apparent from the subsequent detailed description taken in conjunction with the accompanying drawings, wherein:

Fig. 1 is a perspective view of a foot form comprising one specific embodiment of the invention, the article being illustrated in assembled condition with a slipper sock fitted thereon;

Fig. 2 is a side elevational view of the assembled form;

Fig. 3 is a front end view as seen from the left-hand end of Fig. 2;

Fig. 4 is a top plan view of the assembled form;

Fig. 5 is a plan view of the form in collapsed condition suitable for shipping;

Fig. 6 is a rear end view of the collapsed form as seen from the left-hand end in Fig. 5;

Fig. 7 is a rear end view of the form in partially assembled condition;

Fig. 8 is a transverse sectional view as taken along the line 8—8 of Fig. 2; and

Fig. 9 is a plan view on a reduced scale of the blank comprising the form in spread apart condition.

Broadly speaking, the novel collapsible foot form comprising the invention consists of a unitary sheet of lightweight foldable material such as cardboard which is shaped to provide a pair of matching foot and ankle panels integrally hinged together at the upper portion thereof and having means for holding the bottom edges thereof in spread apart relation when the form is assembled. Thus, the hinged panels can be disposed flatwise against each other in collapsed condition of the article and can be assembled to provide a generally triangular body adapted to have a slipper sock or similar article of footwear fitted thereover for displaying the same.

Referring first to Fig. 1 of the drawings, a collapsible cardboard foot form 11 comprising one specific embodiment of the invention is illustrated in assembled condition with a slipper sock 12 fitted thereover in display position.

2

The slipper sock 12 is of a well known type having a knitted upper portion 13 secured to a soft leather lower or sole portion 14. As thus assembled, the foot form holds the slipper sock 12 in distended relation simulating the appearance of the article on the foot of a wearer, and the footwear can thus be displayed attractively on a store counter or in a showcase or show-window.

The display form consists of a unitary sheet of light-weight foldable material such as cardboard, the complete sheet or blank being shown in spread apart condition in Fig. 9 prior to folding and assembly thereof. Thus, the blank or sheet is shaped to provide a pair of complementary panel portions 16 and 17 each of which is designed in this instance to simulate an ankle and foot portion. The panels 16 and 17 have an integral foldable connection along a score line 18 so that the two panels are hinged together along the top edge of the ankle portions to permit flatwise collapsing of the display form with the panels in side-by-side relation as illustrated in Figs. 5 and 6. For limiting the extent to which the panels 16 and 17 may be spread apart during assembly of the article into display condition, the panel 17 is provided with a flap or tab 19 foldably connected along a score line 21 to the instep portion of the panel 17. This tab 19 is bent over and permanently secured, as by a suitable adhesive or the like, to the corresponding instep portion of the opposite ankle and foot panel 16. The instep portion of the latter is cut away or recessed slightly, as at 22, in order to receive the folded over portion of the connecting tab 19 thereby providing a smooth unbroken instep line as seen in Figs. 2 and 5.

For interconnecting the lower edges of the ankle and foot panels 16 and 17 and for holding the same in spread apart relation during assembled condition of the display form, I provide a pair of cooperating foldable sole flaps integrally connected to the panels 16 and 17. Thus, the panel 16 has an elongated tapered sole flap 22 foldably connected to the bottom edge of the panel 16 along a score line 23 and extending from a point adjacent the heel of the panel 16 and terminating rearwardly of the toe portion of the panel 16. A pair of spaced die cut areas 24 are provided along the fold line 23 so as to form slots or openings along the hinged connection 23 when the sole flap 22 is folded inwardly relative to the panel 16 during assembly of the article. The opposite panel 17 has a complementary tapered sole flap 26 foldably secured along a score line 27 to the bottom edge of the panel, but in this instance the sole flap 26 extends from the heel of the panel 17 completely to the end of the toe portion of the panel 17. The sole flap 26 also carries a pair of foldable tabs 28 which are receivable in the slots formed by the die cut areas 24 in the opposite panel (Fig. 8).

As best seen in Figs. 5 and 6, the display form can be collapsed in completely flattened condition for shipping purposes, the respective halves 16—22 and 17—26 of the display form being connected across the top of the ankle portion at 18 and also across the instep portions by the adhesively secured tab 19. To assemble the article for display purposes, the respective sole flaps 22 and 26 are folded inwardly toward each other along the fold lines 23 and 27, respectively, while the bottom edges of the ankle and foot panels 16 and 17 are spread apart so that the body of the form assumes a generally triangular configuration. As best seen in Fig. 7, the inwardly folded sole flaps 22 and 26 are arranged in overlapping relation with the flap 26 underlying the flap 22, and thereafter the connecting tabs 28 on the flap 26 are inserted through the slots formed by the die-cut areas 24 as seen in Fig. 8 thereby interlocking the sole flaps and retaining the bottom portions of the ankle and foot panels in spread apart display relation.

For contributing to the simulated ankle and foot ap-

pearance of the device when in display condition, the forward ends of the panel 16 and 17 are rounded to provide toe portions 29 and 31, respectively. Likewise, the forward end of the lowermost sole flap 26 is rounded, as at 32, in the same general manner as the toe portions 29 and 31. Thus, when the form is completely assembled the triangularly related toe portions 29, 31 and 32 provide in effect a plurality of interfitting generally gore-shaped members which can be pressed together in converging relation to conform to the restricted confines of the toe portion of a slipper sock or similar article of footwear. In this connection the sole flap 22 is somewhat shorter than the flap 26 so that the toe portion 32 of the latter projects beyond the forward end of the flap 22 for greater flexibility of the toe portion 32. As will also be evident from the drawings, the panels 16 and 17 are rounded, as at 33, to simulate the heel portion of the foot.

From the foregoing, it will be seen that my invention provides an inexpensive lightweight collapsible foot form which can be shipped easily and can at the same time be assembled rapidly for effective display of footwear. In displaying a slipper sock 12 of the type seen in Fig. 1, the upwardly projecting ankle portions of the panels 16 and 17 may carry suitable advertising text or indicia. In addition, the ankle portions may be provided with an aperture 34 for tying on an identifying or price tag. For displaying other types of footwear, it will be understood that the upwardly extending ankle portion of the form may be somewhat longer to provide a leg portion when necessary.

Although the invention has been described with reference to a particular structural embodiment thereof, it is to be understood that various modifications and alternative structures may be resorted to without departing from the scope of the invention as defined in the appended claims.

I claim:

1. A footwear display form comprising a pair of complementary panels having the shape of an ankle and foot, means foldably connecting the panels adjacent the upper portions thereof so as to permit the form to be collapsed with the panels disposed flatwise against each other, foldable sole flaps at the lower portions of said panels adapted to be folded inwardly toward each other, and means for securing the folded sole flaps in overlapping relation for

holding the lower portions of said panels in spread apart relation.

2. A collapsible display form for footwear comprising a pair of panels each simulating the shape of an ankle and foot and integrally hinged together adjacent the upper portion thereof, and integral flap means at the bottom edge of at least one of said panels and foldable transversely of the panels for securing the lower portions of the panels in spaced relation whereby to provide a display body of generally triangular cross-section.

3. A collapsible display form for footwear comprising a pair of ankle and foot simulating panels, means hingedly connecting said panels adjacent the upper edges thereof to permit collapsing of the panels, and means integral with the panels for detachably holding the lower edges of the panels in spread apart relation whereby to provide an assembled display body of generally triangular cross-section.

4. A footwear display form comprising a pair of flat panels each simulating the shape of an ankle and foot with an instep portion, said panels having an integral foldable connection adjacent the ankle to permit collapsing of the panels flatwise against each other, means hingedly connecting said panels together across the instep portions thereof, and collapsible means for holding the bottom edges of said panels in spread apart relation during assembled condition of the form.

5. The article of claim 4 further characterized in that said collapsible means comprises a pair of sole flaps foldably connected to said panels and adapted to extend in overlapping relation between the bottom edges of said panels.

6. The article of claim 4 further characterized in that said first-named means comprises a foldable tab extending from one of said panels and fastened to the other of said panels.

7. The article of claim 1 further characterized in that said last-named means comprises detachable interlocking tab and slot portions.

8. The article of claim 2 further characterized in that said panels and said flap means are formed with generally gore-shaped forward end portions adapted to be pressed into converging relation for simulating a toe portion.
